UNITED STATES PATENT OFFICE.

ALLIE R. WELCH, DECEASED, LATE OF PONTIAC, MICHIGAN, BY MARY E. WELCH,
SPECIAL ADMINISTRATRIX, OF PONTIAC, MICHIGAN.

SIGNAL FOR AUTOMOBILES.

1,162,421.

Specification of Letters Patent. Patented Nov. 30, 1915.

Application filed December 18, 1913. Serial No. 807,505.

To all whom it may concern:

Be it known that I, MARY E. WELCH, a citizen of the United States, residing at Pontiac, county of Oakland, State of Michigan, 5 am administratrix of the estate of ALLIE R. WELCH, deceased, late of Pontiac, Michigan, who has invented a certain new and useful Improvement in Signals for Automobiles, and declare the following to be 10 a full, clear, and exact description of the same, such as will enable others skilled in the art to which it pertains to make and use the same, reference being had to the accompanying drawings, which form a part of 15 this specification.

The invention relates to signals, and the special object of the improvements is to provide an improved signal which may operate in conjunction with the cooling fan, 20 and one in which the signal is one quality of sound which is produced immediately when the device is actuated for that purpose.

In the accompanying drawings there is 25 illustrated a signal in which the sound is produced by vibration of the air.

Figure 1 shows a section of the apparatus embodying the invention, a portion of the cooling fan and adjacent parts, the section 30 being taken in the planes indicated by the lines A—A Fig. 2. Fig. 2, is a detailed elevation of the same, looking from the right of Fig. 1, and partly broken away. Fig. 3, is a section on the line C—C of Figs. 1 and 35 2. Figs. 4, 5 and 6 are entirely similar, respectively, to Figs. 1, 2 and 3 but illustrate a slightly modified construction.

a is a standard for supporting the cooling fan for an automobile.

40 b is a stationary arbor secured in the upper end of the standard a and extending horizontally therefrom.

c is a pulley sleeved upon the arbor b, and d is the hollow hub of the fan secured rigidly to the pulley c.

45 e e are the radially extending fan blades. These blades are hollow and open to the outer air at their outer ends and to the hollow of the hub d at their inner ends. In the

50 example shown in Figs. 1, 2 and 3 there is illustrated a metal fan, constructed as shown in cross section in Fig. 3, that is to say, having the dished back q and the flat face p, the space between these forming the hollow

in the fan blade. There is a drum having 55 a cylindrical part h, and the web r closing the inner end of this cylindrical part. The drum h fits and is secured within the hub d so that its cylindrical portion is interposed between the inner portion of said hub and 60 the openings to the fan blades e. There are a series of rectangular slots j, extending through the cylindrical wall of the drum h r, parallel to the axis thereof. There is a second drum g fitting within the drum 65 h r, with its cylindrical wall against the interior surface of the cylindrical wall of the drum h r. There are slots i cutting through the cylindrical portion of the drum g parallel to the slots j and so located that 70 they shall register with said slots at certain angular positions and be closed at other angular positions. The drum g has a web s 75 closing its inner end, its outer end being open to the atmosphere.

m is a rod passing through an axial aperture through the arbor b. The rod m may turn and slide longitudinally in said arbor. The drum g is secured upon the rod m by its web s.

o is a friction disk interposed between the web s and the flange n on the arbor b. Of course the periphery of the drum may be conical as shown in the modification illustrated in Figs. 4, 5 and 6, or other equivalent 85 surface of revolution.

The operation of the above described device is as follows: The fan is rotated through the pulley c in the usual way. The rotation of the fan blades causing a draft 90 outward therethrough. In the ordinary working of the fan the drum g is carried therewith because of the friction of its wall against the cylindrical wall h secured in the hub of the fan. When it is desired to sound 95 the signal the rod m is drawn in forcing the web s against the friction disk o and the latter against the flange n so as to hold the drum g from rotation. Under these circumstances the slot i registers with the 100 slots j and are alternately closed and opened by the wall h of the drum h r. Under these conditions the rapid passing of air through the slots i j sounds the signal.

By the above described device in which 105 the sound is caused by the relative rotation of two parts, one of which normally rotates with the other and the relative rotation

being caused by the stopping of the last named part, the signal is sounded immediately at a pitch corresponding to the amount of braking force applied thus imparting a 5 human element to the tone allowing the expression of feelings to be interpreted. The sound can be varied by fully or partially braking or stopping the drum.

While the above construction is shown as 10 illustrating the invention, it is not intended to confine the scope of the invention to the details shown, as the invention may be embodied in various equivalent mechanism.

What is claimed is:

15 1. In an apparatus of the kind described, a rotating part, a second part yieldingly connected with the first part so as to rotate therewith, means for retarding the motion of the second part to the extent required, 20 and means whereby the relative motion of said parts shall produce an audible signal, the pitch of the sound of which varies with the rate of relative motion of said parts.

2. The combination of a fan provided 25 with blades with radial passages therethrough, a siren normally rotating with said fan and adapted to be operated by a draft of air through said passages.

3. The combination of a fan having 30 blades with radial passages therethrough, said blades being formed at a part of their outer surface to actuate a current of air, means for rotating said fan, and a signal adapted to be sounded by the draft of air 35 through said passages caused by the rotation of said fan.

4. The combination of a fan having blades, radial passages through said blades, means for rotating said fan and a signal 40 located upon said fan adapted to be sounded by the draft of air through said passages caused by the rotation of said fan.

5. The combination of a fan having blades with radial passages therethrough, 45 means for rotating said fan and a signal of which a part of said fan forms a constituent part adapted to be sounded by the draft

of air through said passages caused by the rotation of said fan.

6. The combination of a fan provided 50 with blades having radial passages therethrough, a siren normally rotating with said fan and adapted to be operated by a draft of air through said passages, said siren consisting of two parts and means for checking 55 or holding the motion of one of said parts to operate the siren.

7. The combination of a fan provided with blades having radial passages therethrough, a siren normally rotating with said 60 fan and adapted to be operated by a draft of air through said passages, said siren consisting of two parts and means for retarding one of said parts to produce a signal at will or vary the tone.

8. The combination of a fan provided with blades having radial passages, a siren normally rotating with said fan and adapted to be operated by a draft of air through said passages, and means for varying the 70 draft of air through said fan so constructed that it may be manipulated when the fan is in motion.

9. The combination of a fan having radially extending blades provided with passages therethrough, means for rotating said fan, a hollow hub for said fan, a wall interposed between the inner openings to said passages and the interior of said hub, a cylinder, said cylinder being provided with 80 slots, a second cylinder provided with slots fitting within the first named cylinder, said slots being adapted to register with the slots in the first named cylinder and a brake for checking the rotation of the second cylinder. 85

In testimony whereof, I sign this specification in the presence of two witnesses.

MARY WELCH,
*Administratrix of the estate of Allie R.
Welch, deceased.*
